US00D861698S

(12) **United States Design Patent** (10) Patent No.: **US D861,698 S**
 Fenton et al. (45) Date of Patent: ** Oct. 1, 2019

(54) **CASE FOR A LAP-TOP SHAPED PORTABLE ELECTRONIC COMPUTING DEVICE**

(71) Applicant: **Pioneer Square Brands, Inc.**, Seattle, WA (US)

(72) Inventors: **Timothy John Fenton**, Mercer Island, WA (US); **Gary Allen Ashley**, Seattle, WA (US)

(73) Assignee: **PIONEER SQUARE BRANDS, INC.**, McLean, VA (US)

(**) Term: **15 Years**

(21) Appl. No.: **29/679,166**

(22) Filed: **Feb. 1, 2019**

CLAIM

The ornamental design for a case for a lap-top shaped portable electronic computing device, as shown and described.

DESCRIPTION

FIG. 1 is a top perspective view of a a case for a lap-top shaped portable electronic computing device showing our new design.

FIG. 2 is a top plan view thereof.

FIG. 3 is a bottom plan view thereof.

FIG. 4 is a front elevation view thereof.

FIG. 5 is a rear elevational view thereof.

FIG. 6 is a left elevational view thereof; and,

FIG. 7 is a right elevational view thereof.

The features shown in broken lines in the drawing figures depict features that form no part of the claimed design.

1 Claim, 3 Drawing Sheets
